UNITED STATES PATENT OFFICE.

MITCHELL SHARP, OF DUNMORE, WEST VIRGINIA.

RAIL-JOINT.

1,226,819.

Specification of Letters Patent. Patented May 22, 1917.

Application filed January 31, 1917. Serial No. 145,664.

To all whom it may concern:

Be it known that I, MITCHELL SHARP, a citizen of the United States, residing at Dunmore, in the county of Pocahontas, State of West Virginia, have invented a new and useful Rail-Joint; and I do hereby declare the following to be a full, clear, and exact description of the invention, such as will enable others skilled in the art to which it appertains to make and use the same.

The present invention relates to certain new and useful improvements in rail joints, and has for its object to provide a device of this character which embodies novel features of construction whereby the abutting rail ends are held securely against both vertical and lateral displacement, and the use of bolts and screws is avoided.

Further objects of the invention are to provide a rail joint which is comparatively simple and inexpensive in its construction, which admits of the rail ends being readily placed together or separated, which provides a strong and rigid joint.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a rail joint constructed in accordance with the invention.

Fig. 2 is a horizontal sectional view on the line 2—2 of Fig. 1.

Fig. 3 is a transverse vertical sectional view on the line 3—3 of Fig. 2.

Fig. 4 is a detached perspective view of one of the locking blocks.

Fig. 5 is a similar view of one of the rail ends.

Corresponding and like parts are referred to in the following description and indicated in all the views of the drawings by the same reference characters.

Specifically describing the present embodiment of the invention, the numeral 1 designates the abutting ends of a pair of rails which may be of the conventional cross section and include a head and base connected by a centrally disposed and comparatively thin vertical web member. The rails

are supported in the usual manner by ties 2 and secured in position thereon by suitable fastening members such as the spikes 3. Metal bearing plates 4 may be interposed 69 between the rails and the ties, if desired.

Each of the rail ends 1 has a pair of longitudinally disposed slots 5 in the web thereof, and is formed with a longitudinally extending projection 6 which is offset laterally from the web and arranged to fit closely against the web of the abutting rail end. These extensions 6 are preferably formed integral with the respective rail ends, and are in longitudinal alinement with the before 70 mentioned slots 5. Each of the extensions 6 carries a pair of L-shaped lugs 7, said lugs being arranged to pass laterally through the slots 5 of the other rail end when the two rail ends are slightly separated, and to interlock with the ends of the said slots 5 when the rail ends are moved toward each other. The lengths of the slots 5 are substantially 75 the same as the lengths of the bases of the L-shaped lugs 7, and the spacing of the slots 80 and lugs is the same. With this construction and to interlock with the ends of the said slots 5 when the rail ends are moved toward each other. The lengths of the slots 5 are substantially the same as the lengths of the bases of the L-shaped lugs 7, and the spacing of the slots 85 and lugs is the same. With this construction it will be obvious that when the rail ends are slightly separated, the L-shaped lugs 7 of the web extensions 6 can be inserted laterally through the slots 5 of the opposite rail ends, after which a slight longitudinal movement of the rail ends toward each other will cause the hooked ends of the L-shaped lugs to interlock with the ends of the slots 90 5 in such a manner as to hold the rail ends securely against relative lateral or vertical movement. In order to lock the L-shaped lugs 7 in operative position, locking blocks 95

8 may be inserted in certain of the slots 5 between the ends of the slots and the backs 95 of the L-shaped lugs 7, thereby preventing the L-shaped lugs from moving longitudinally within the slots and becoming disengaged therefrom. These locking blocks 8 are shown as formed with spring arms 9 100 which are adapted to be inserted through openings 10 in the web extensions 6, said arms terminating in rounded noses 9^a which are arranged to expand and engage the edges of the opening 10 to hold the locking 105 block in operative position. It will be obvious, however, that the locking block can be forcibly inserted in position or removed therefrom, that it is not liable to be dislodged by vibration, and that by the use of 110 this construction the necessity of employing screws or bolts is entirely avoided.

Having thus described the invention, what I claim as new and desire to secure by Letters Patent, is:—

1. A rail joint including the abutting ends 5 of a pair of rails, said rail ends being provided with slots, a laterally offset extension projecting longitudinally from each rail and fitting against the side of the other rail, an L-shaped lug carried by each extension 10 and interlocking with the slot of the other rail, and locking means for holding the L-shaped lugs in operative position.

2. A rail joint including the abutting ends 15 of a pair of rails, said rails being provided with slots, a laterally offset extension projecting longitudinally from each rail and fitting against the side of the other rail, an L-shaped lug carried by each extension and adapted to be inserted through the longitudinal slot of the other rail and moved longitudinally into an interlocking engagement 20 with one end thereof, and locking blocks inserted in the slots of the rails back of the L-shaped lugs for holding the latter in operative position.

3. A rail joint including the abutting ends 25 of a pair of rails, said rails being provided in the webs thereof with longitudinal slots, a lateral offset extension projecting longitudinally from each rail end and fitting 30 against the side of the other rail, an L-shaped lug carried by each extension and adapted to be inserted through the longitudinal slot of the other rail and moved longitudinally into engagement with one end 35 of the slot, the extension being provided with an opening adjacent the back of the

L-shaped lug, locking blocks insertible within the longitudinal slots of the rails back of the L-shaped lugs for holding the latter 40 in operative position, and spring arms carried by the locking blocks and insertible through the openings of the extensions to hold the locking blocks in operative position.

4. A rail joint including the abutting 45 ends of a pair of rails, said rails having longitudinally extending slots in the webs thereof, a laterally offset extension projecting longitudinally from the web of each rail end and arranged in alinement with the 50 slots, L-shaped lugs carried by each extension and arranged to be inserted through the longitudinal slots of the other rail and brought into an interlocking engagement with the ends of the slots by a longitudinal 55 movement of the rail ends, said extensions being provided at points adjacent the back of certain of the L-shaped lugs with openings, locking bolts insertible within certain of the slots back of the L-shaped lugs to 60 hold the latter in operative position, and a pair of spring arms projecting from each of the locking blocks for engagement with the before mentioned openings of the extensions to hold the locking blocks in operative 65 position.

In testimony whereof I have signed my name to this specification in the presence of two subscribing witnesses.

MITCHELL SHARP.
